ENGINE STARTER GEARING

Everett E. Baldwin, Elmira, N. Y., assignor to
 Bendix Aviation Corporation, South Bend, Ind.,
 a corporation of Delaware

Application November 26, 1938, Serial No. 242,545

4 Claims. (Cl. 74—7)

The present invention relates to engine starter gearing and more particularly to a starter drive incorporating an elastic element which is placed under tension by the transmission of starting torque.

5 A divisional application covering more particularly the structure described in Figs. 4 to 8 hereof was filed on October 1, 1940, and given Serial Number 359,259.

10 The increasing strictness of space limitations with respect to automotive engine auxiliaries has emphasized the desirability of reducing the size, and particularly the overall length of starter drives without affecting their torque capacity or operating characteristics. Various forms of 15 starting devices utilizing yielding driving members of elastically deformable material such as rubber under compression has been suggested. It has been found, however, that such members 20 are subject to abrasion by rubbing on the walls of their containers, causing disintegration of the members and sticking of the drives due to the accumulation of rubber particles on the working surfaces. Moreover, when the yielding member 25 is compressed, its end portions become wedged in their seats so as to interfere with the deformation and displacement thereof so that when the drive is under load, the elasticity of the yielding member is confined substantially to its central 30 portions, and the member is not uniformly stressed throughout its length.

The perfection of methods for bonding rubber and rubber substitutes to metal has permitted the use of such materials in situations in which 35 they have not hitherto been available, and it is now proposed to utilize this advanced technology in producing a starter drive incorporating both dimensional and operative improvements.

It is an object of the present invention to provide 40 a novel engine starter drive which is small and compact in comparison to earlier types of drives having equal torque capacity.

It is another object to provide such a device which has improved operating characteristics 45 particularly in respect to the yielding driving connection.

It is a further object to provide such a device which is efficient and reliable in operation while being simple and economical in construction.

50 It is another object to provide such a device incorporating a member of elastically deformable material which is placed under tension when torque is transmitted through the drive.

55 It is another object to provide such a device in which the elastic member is subjected to both

tension and torsion during the cranking operation.

Further objects and advantages will be apparent from the following description taken in connection with the accompanying drawings in which:

Fig. 1 is a side elevation partly in section of a starter drive embodying a preferred form of the invention, showing the parts in idle or disengaged position;

Fig. 2 is an end elevation of the same;

Fig. 3 is a substantially mid-sectional view of the structure illustrated in Fig. 1, showing the parts in operative position and showing an optional form of reentry device for the pinion member;

Fig. 4 is a view similar to Fig. 1 of a second embodiment of the invention;

Fig. 5 is a section taken substantially on the line 5—5 of Fig. 4;

Fig. 6 is a side elevation partly in section of a third embodiment of the invention showing the parts in idle position;

Fig. 7 is an end view thereof; and

Fig. 8 is a view similar to Fig. 6, showing the parts in driving position.

In Fig. 1 of the drawings there is illustrated a power shaft 1 which may be the extended armature shaft of the starting motor, not shown. A flange or disc member 2 having a flat radial flange 3 is fixed to the power shaft by suitable means such as a pin 4 retained by an elastic ring 5 seated in a peripheral groove in the pin and flange member. A combined pinion and screw shaft member 6 is slidably journaled on the power shaft 1 for movement into and out of engagement with a member such as a flywheel ring gear 7 of an engine to be started.

The member 6 comprises a pinion portion 8 adapted to engage the flywheel gear 7 and a screw-threaded cylindrical portion 9 extending toward the flange member 2. The member 6 is normally maintained by an anti-drift spring 11 in its idle position as shown, this position being defined by suitable means such as a stop member 12 located on the power shaft 1 by means of a set screw 14.

A barrel member 15 is arranged to surround and partially enclose the flange member 2, and is provided with a radially inwardly extending flange 16, the inner periphery of which normally rests on a smooth portion 17 on the end of the screw shaft 9. The flange 16 is internally threaded as indicated at 18 to engage the threads of the screw shaft 9 upon relative rotation thereof.

A cylindrical transmission member 19 of elastically deformable material such as rubber is located within the barrel member 16 and has its ends bonded in any suitable manner to the flanges 3 and 16 as indicated at 21 and 22 respectively whereby separation and relative rotation of these flanges and accordingly of the flange member 2 and barrel 16 are yieldingly opposed by the transmission member.

10 The screw-shaft 9 is so dimensioned that when the pinion 8 is in full operative engagement with the flywheel gear 7, the end 23 of the screw shaft comes into abutting relation with the flange 3 of the member 2 whereby the

15 operative position of the pinion on the power shaft 1 is defined. A thrust washer 24 is preferably interposed between the screw shaft and flange member.

The extension of the transmission member 19 is preferably limited by positive means such as a thrust ring 25 located in the barrel member at its open end, in position to engage the flange 3 and prevent its withdrawal from the barrel member.

20 In the operation of this embodiment of the invention, starting with the parts in the positions illustrated in Fig. 1, rotation of the power shaft 1 in the direction of the arrow causes rotation of flange member 2, transmission member 19 and barrel member 16. This rotation causes the flange 16 to thread itself on the screw shaft 9, thus drawing the pinion 8 into engagement with the engine gear 7, at which time the end 23 of the screw shaft engages the thrust washer 24 as shown in Fig. 3. Further rotation of the power shaft causes torque to be yieldingly transmitted to the pinion 8, such transmission being cushioned by the stretching and the torsional resilience of the transmission member 19.

25 When the engine starts, the overrunning of the pinion and screw shaft member 6 causes it to thread itself back to its idle position, running out of the threads 18 in the flange 16 and thereafter rotating idly until its momentum is dissipated. Reentry of the screw shaft 9 into the threads 18 upon reactuation of the starter drive may be assured by assembling the parts with the transmission member 19 under a slight degree of compression when the threads of the screw shaft 9 are withdrawn from the flange 16 of the barrel member. If preferred, a remeshing spring 13 may be interposed between the pinion 8 and the stop member 12 as illustrated in Fig. 3.

30 In the embodiment of the invention illustrated in Fig. 4, the pinion is arranged to travel away from the yieldable coupling when moving into engagement with the engine member instead of toward said coupling as in the embodiment first described.

35 In Fig. 4 a power shaft 31 has fixed thereon a drive member 32 by suitable means such as a pin 33, and a pinion member 34 is slidably journaled on the power shaft for movement into and out of engagement with a member such as a flywheel gear 35 of an engine to be started. Pinion 34 has a tubular threaded extension 36 suitably fixed thereto as by welding as indicated at 37, and a screw shaft 38 is slidably journaled on the power shaft 31 in threaded engagement therewith.

40 A barrel member 39 is arranged to surround the threaded members and the drive member 32 and is fixedly connected to the drive member 32 for rotation therewith as by means of radial lugs

41 of the drive member fitting within notches 42 in the end of the barrel and retained therein by suitable means such as a split ring 43.

A flange member 44 is rigidly mounted in the opposite end of the barrel by means of radial lugs 45 seated in notches 46 in the barrel and retained therein by means of a lock ring 47. A flange member 48 is rigidly connected to the screw shaft 38 as by welding as indicated at 49, and a yielding transmission element 51 of elastically deformable material is suitably bonded as indicated at 52 and 53 to the flanges 44 and 48 respectively to form a yielding driving connection therebetween.

45 The idle position of the pinion 34 is defined by its abutment with the end 54 of the screw shaft, in which position it is normally maintained by an anti-drift spring 55. The operative position of the pinion is defined by a stop member 56 located on the power shaft 31 by 20 means of a thrust ring 57 seated in a groove 58 in the shaft.

50 In the operation of this embodiment of the invention, rotation of the power shaft 31 is transmitted through the drive member 32, barrel 39, flange member 44, transmission member 51 and flange member 48 to the screw shaft 38. The pinion 34 is thereupon projected toward the flywheel gear 35 by the cooperation of its threaded extension 36 with the screw shaft 38 whereby the pinion is moved into operative position against its stop 56. Longitudinal movement of the pinion being thus interrupted, rotation is transmitted thereto from the power shaft 31 by virtue of the stretching of the yielding transmission member 51 by backward movement of the screw shaft 38, and also by the torsional elasticity of the transmission member. Stretching of the transmission member is limited by engagement of the end of the screw 40 shaft 38 and flange member 48 with a thrust washer 59 seated against the driving member 32, after which engagement the operation of the drive is cushioned further by the torsional elasticity of the transmission member.

55 In the embodiment of the invention illustrated in Figs. 6, 7 and 8 the drive is arranged so that when in idle position, the pinion is completely housed within the drive, so as to make a very short compact form of drive.

60 As illustrated in Fig. 6 a power shaft 61 has fixed thereon a driving member 62 as by means of a pin 63. A pinion 64 is slidably journaled on the power shaft for movement into and out of engagement with an engine flywheel gear 65, and has a screw shaft 66 rigidly fixed thereto as by welding at 67.

65 A barrel member 68 is arranged to enclose the parts of the drive, and is rigidly connected to the drive member 62 by means of a disc 69 welded to the driving member as indicated at 71 and having radial lugs 72 extending into notches 73 in the end of the barrel and held therein by means of a lock ring 74.

70 A flange member 75 is rigidly fixed in the other end of the barrel as by means of radial lugs 76 seated in notches 77 and maintained therein by means of a lock ring 78. A hollow threaded sleeve 79 is mounted on the screw shaft 66 and has a flange member 81 fixed thereto as by welding as indicated at 82. Flange members 75 and 81 are yieldingly connected by means of a transmission member 83 of elastically deformable material bonded as indicated at 84 and 85 to the flanges 75 and 81 respectively.

The threaded sleeve 79 is preferably provided with a smooth counterbored portion 86 permitting the screw shaft to run off the ends of the threads in the sleeve when the pinion overruns the drive. A reentry spring 87 is provided for maintaining initial engagement of the threads of the screw shaft with the threads of the sleeve, and an anti-drift spring 88 is provided for yieldingly maintaining the pinion in its idle position. In this embodiment of the invention, the operative position of the pinion is defined by the abutment of the forward end 91 of the screw shaft against the flange member 75.

In operation, rotation of the power shaft 61 is transmitted through drive member 62, disc 69, barrel 68, flange member 75, transmission member 83 and flange 81 to the threaded sleeve 79. The pinion 64 and screw shaft 66 are thus caused to be threaded out of the barrel into engagement with the engine gear 65 until the end of the screw shaft abuts the flange member 75. Rotation is thereupon transmitted to the pinion yieldingly by virtue of the stretching and torsional elasticity of the transmission member 83. The stretching of the transmission member is limited by engagement of the flange 81 with a thrust washer 92 seated against the disc 69 of the driving member.

When the engine starts, overrunning of the pinion causes it to be threaded back into the sleeve 79 until the screw shaft 66 runs off the ends of the threads in the sleeve. The pinion and screw shaft can then overrun freely until their momentum is dissipated, after which initial engagement of the threads is effected by the reentry spring 87, the parts being maintained in their idle positions as illustrated by the anti-drift spring 88.

Although certain embodiments of the invention have been shown and described in detail, it will be understood that other embodiments are possible and various changes may be made in the arrangements and proportions of the parts without departing from the spirit of the invention as defined in the claims appended hereto.

What is claimed is:

1. In an engine starter drive, a power shaft, an engine driving member slidably journaled thereon, and means responsive to acceleration of the power shaft for moving the engine driving member into operative position including a flange member having an inclined connection with the engine driving member, a member rigidly connected to the shaft in advance of the flange member in the direction of travel of the engine driving member toward operative position, a block of elastically deformable material bonded at its ends to the flange member and the rigidly connected member respectively, and thereby forming a tensile connection therebetween, and stop means independent of the flange member for defining the operative position of the engine driving member and cooperating with

the inclined connection of the engine driving member to cause the driving torque to stretch the elastic block and thereby form a yielding driving connection.

2. In an engine starter drive, a power shaft, 5 an engine driving member slidably journaled thereon, and means responsive to acceleration of the power shaft for moving the engine driving member into operative position including a flange member having a threaded connection with the 10 engine driving member, a second flange member rigidly connected to the shaft in advance of the threaded flange member in the direction of travel of the engine driving member into operative position, a block of elastically deformable material bonded at its ends to said flange members and thereby completing a tensile connection between the power shaft and engine driving member, and stop means independent of the first-mentioned flange member, engage- 15 20 able by the engine driving member when in driving position.

3. In an engine starter drive, a power shaft, a driving member fixed thereon, a pinion member slidably journaled on the power shaft, a 25 flange member, an elastic member attached at its ends to the driving member and flange member, said flange member having a threaded connection with the pinion member operative upon acceleration of the power shaft to draw the pinion into mesh with a member of an engine to be started, said pinion being arranged to run out of the threads in the flange member when the pinion member overruns the drive, and means whereby said overrunning action causes 30 35 a slight compression of the elastic member, causing it to ensure reengagement of the threads of the flange and pinion members upon reactuation of the drive.

4. In an engine starter drive, a power shaft, 40 a driving member fixed thereon, a pinion member slidably journaled on the power shaft, a flange member, a cylindrical block of elastically deformable material attached at its ends to the driving member and flange member and forming the sole operative connection therebetween, said flange member having a threaded connection with the pinion member operative upon acceleration of the power shaft to draw the pinion into mesh with a member of an engine to 45 50 be started, said meshing action being cushioned by the stretching of the elastically deformable block, said pinion being arranged to run out of the threads in the flange member when the pinion member overruns the drive, and an abutment on the power shaft so defining the idle 55 position of the pinion that said overrunning action causes a slight compression of the elastic block, causing it to ensure reengagement of the threads of the flange and pinion members upon 60 reactuation of the drive.

EVERETT E. BALDWIN.
